UNITED STATES PATENT OFFICE.

ALPHONSO L. CHANDLER, OF CHICAGO, ILLINOIS.

MITER-BOX.

SPECIFICATION forming part of Letters Patent No. 680,021, dated August 6, 1901.

Application filed September 8, 1900. Serial No. 29,387. (No model.)

To all whom it may concern:

Be it known that I, ALPHONSO L. CHANDLER, a citizen of the United States, residing at Chicago, in the county of Cook and State 5 of Illinois, have invented a certain new and useful Improvement in Miter-Boxes, of which the following is a specification.

This invention has for its objects to improve the construction of the bed of a miter-box of that class in which a swinging saw-guide is employed for giving the angle of the cut, to enable the angle of cut to be made more acute than would be the case in the ordinary operation of the saw-guide, to enable 10 moldings having a groove or channel on the rear face to be maintained level in giving the angle cut, to adjust and guide the saw properly in relation to the cut, and to improve generally the construction and operation of 15 the various parts which enter into the construction of the miter-box as a whole.

The invention consists in the features of construction and combination of parts hereinafter described, and pointed out in the 20 claims.

In the drawings illustrating the invention, Figure 1 is a top or plan view of the miter-box; Fig. 2, a cross-sectional elevation on line 2 of Fig. 1 looking in the direction of the 25 arrow; Fig. 3, a vertical central section through one of the saw-guide boxes, showing the saw-guide and its adjustable support in elevation and taken on line 3 of Fig. 1 looking in the direction of the arrow; Fig. 4, a 30 cross-section through one of the saw-guides and its support, taken on line 4 of Fig. 3 looking in the direction of the arrow; Fig. 5, a cross-section through the bed or base of the miter-box, taken on line 5 of Fig. 1 looking 35 in the direction of the arrow; Fig. 6, a cross-section of the bed or base of the miter-box, taken on line 6 of Fig. 1 looking in the direction of the arrow; Fig. 7, a detail, being a vertical longitudinal section taken on line 7 40 of Fig. 6 looking in the direction of the arrow; and Fig. 8, a detail, being a longitudinal central section of the lock for the saw-frame, taken on line 8 of Fig. 3 looking in the direction of the arrow.

The miter-box is to be constructed with a bed or base frame A, having side rails and

end pieces in the arrangement shown, but can be of other construction so long as it furnishes a support for the material or strip to be acted upon and for carrying the operating 55 parts. The bed or base frame at each end, as shown, is supported on legs or standards a and is depressed at the center, so as to form a quadrant A', and, as shown, between the side lines of the quadrant and the outer end 60 piece a piece or block of wood or other suitable material A² is inserted, and this piece or block can be sanded or otherwise roughened on its upper face, so as to give a resistance which will prevent the easy slipping or dis- 65 placement of the material when in position on the bed or base frame. At the rear of the bed or base frame on each side of the center is a back or guide strip B, each strip pivoted at its inner end to the bed or base frame and 70 having at its outer end a stem or bolt B', which passes through a curve b in the end piece of the bed or base frame and has its projecting end screw-threaded to receive a winged clamping-nut b', by means of which the back or guide 75 strip can be firmly held in an adjusted position. Each strip can be swung forward, so as to stand at an angle in relation to the straight plane of the bed or base frame, as shown, by the back or guide strip at the left hand of 80 Fig. 1, and when swung forward it produces a change in the angle of cut for the piece of material by deflecting the line at which the material stands in relation to the angle of the quadrant, giving a more acute angle of cut 85 than with the parts in their normal position, with the back or guide strip parallel with the bed or base frame, in which position the cut will be at an angle between ninety and forty-five degrees, while with the back or guide strip 90 set inclined an acute angle between ninety and forty-five degrees or even more than ninety degrees can be attained. At the rear of the bed or base frame, on each side of the center and just forward of each back or guide strip, 95 is an adjustable rest or support C, which can be raised by screws C', the stems of which enter into the screw-threaded sockets c' on plates c, secured in the top of each rest or support, and the screw is held against advancing when 100 turned by a plate c², which engages with a groove c³ in the body of the screw. As shown,

adjusting-screws are provided one at each end of the rest or support, so that the rest or support will be uniformly and regularly raised its entire length, so as to be in a level plane on its upper face, and each rest or support can be raised and lowered by turning the adjusting-screws in the proper direction. These rests or supports furnish a bearing for maintaining strips of molding or other material which have a groove or channel on the under face in a level position by raising the rests or strips until they abut against the under face of the groove or channel, as shown in Fig. 6, thereby giving a firm support for the molding or other piece of material against tipping and furnishing a bearing for the strip or piece of material its entire width when in place on the bed or base frame, as shown in Fig. 6. Each rest or support can be lowered, so as to have its upper face in a plane with the upper face of the bed or base frame, as shown in Fig. 5, giving a level support or bearing for moldings or strips having a flat under face. The adjustable rests or supports enable molding and material having a channel or groove to be cut at an angle readily and easily and without any trouble, as the molding or strip has a firm support on the bed or base frame its full width.

The saw-frame is located so as to swing coincident with the quadrant and is formed of a main cross-piece D, pivoted at a point or pivot d to the bed or base frame, which point or pivot is located at the center of the circle for the quadrant. At each end of the main cross-piece is located a post or upright E, each post or upright having a channel or passage E', in which is located a slide F, having a tongue f, which passes through a slot e in the wall of the post or upright and has attached thereto the saw-guide G, which guide has a vertical slot g for the blade of the saw and an opening g' for the back of the saw, as shown in Fig. 3. Each post or upright E at its lower end has entered thereinto an adjusting-screw F', which contacts the lower end of the slide and by means of which the descent of the slide can be limited at any point desired to bring the saw-guide in proper relation to the material for the effective work of the saw on the material. The saw-guide is located directly above a strip D', which swings with the main cross-piece and is attached in position within the space of the quadrant by the pin or pivot-bolt d and a screw d², and this strip has in its upper face a groove or recess d' in line with the guide-slot g for the admission of the teeth of the saw and so that the saw can be made to completely sever the strip of material in making the angling cut. The slides are each movable in the posts or uprights and can be raised to the full limit of their length, if so desired, which will enable a thick piece to be placed in position on the bed or base frame to be operated upon by the saw, which is desirable in the operation of a miter-box. The saw-guides are arranged far enough away from

the posts E to prevent the packing of sawdust and consequent interference with the easy movements of the saw.

The saw-guide formed as a whole, when swung to the angle desired for the cut, should be locked and held firmly in its swung position, and for this purpose a sliding catch or latch H is provided, having an acting end h, which enters notches h', formed in the edge of the front member of the quadrant, which notches can be spaced so as to produce a swing of fifteen, thirty, and forty-five degrees, or additional notches can be formed in the edge of the front member of the quadrant for intermediate degrees, if so desired, and when the latch or catch at its acting end is engaged with a notch the guide-frame as a whole will be held in the angle of the notch engaged for the operation of making the cut. The latch or catch is simply mounted on the lower or main cross-piece of the saw-frame and, as shown, is held between a plate or strip H' and the top of the main cross-piece and between guides h² on the top of the cross-piece, as shown in Figs. 1 and 2. The body of the latch or catch has a slot or opening H², in which is located a coiled spring I, one end of which abuts against the end slot of the latch or catch and the other against a stud or guide I', extending up from the face of the main cross-piece, as shown in Fig. 8. The spring permits the latch or catch to be retracted, and when released the spring acts and projects the latch or catch for its acting end to enter and engage a notch on the edge of the quadrant to hold the saw-frame in its swung position until the latch or catch is released.

It will be seen that by means of the swinging back or guide-strip the molding or other material to be operated upon can have its relation changed so as to give an acute angle of cut, which, in connection with the quadrant, enables any desired angle of cut to be made. It will also be seen that by means of the adjustable rests or supports at the rear of the bed or base frame rabbeted strips or strips having grooves or channels on their under faces can be firmly supported for operation and that such support will be of the full width of the piece of molding or other material, as the rest or support completes the bearing when elevated to abut against the face of the rabbet. It will also be seen that the saw-frame as a whole swings from a pivot coinciding with the center of the circle of the quadrant and that the main cross-piece or support of the frame is below the bed or base frame and out of the way, while the upper cross-piece is within the plane of the bed or base frame at the quadrant center and out of the way and free to swing below the molding or other material being operated upon. It will also be seen that the guides for the saw can be raised for the admission of thick material, permitting such material to be operated upon, and that the descent or drop of the guides for the saw can be limited and ad-

justed to the point required for the most effective and reliable work in making the cut, and it will also be seen that the saw-frame as a whole can be swung to the angle desired and when in position will be locked and held by the latch or catch. All of these features which enter into the construction of the miter-box of my invention are desirable and of great advantage and benefit in the operation of miter-boxes.

What I regard as new, and desire to secure by Letters Patent, is—

1. In a miter-box, the combination of a bed or base frame, an adjustable rest or support for each half of the box endwise at the rear side of the bed or base frame, screw-threaded sockets inserted in each rest or support, one socket adjacent to each end of the rest or support, and adjusting-screws one for each screw-threaded socket each screw passing through and rotatably supported on the rear side rail of the bed or base frame and entering its screw-threaded sockets, for the screws to operate and raise and lower the rests or supports, substantially as described.

2. In a miter-box, the combination of a bed or base frame having in its upper surface a depressed quadrant-shaped transverse center formed by cutting away the upper face of both the front and rear side rails each side of the transverse center of the box on converging lines from front to rear and diagonal cross-pieces extending from side rail to side rail and converging from front to rear parallel with the convergence of the cut-away ends of the side rails, each diagonal cross-piece having its upper face in a plane with the upper faces of the cut-away sections of the rails, a bar on the under side of the bed or base frame pivoted at its rear end on the center line and at the apex end of and swinging beneath the depressed center, a vertical post at each end of the bar, each post having a vertical passage rectangular in cross-section open at the top and closed at the bottom and each post having a lateral slot through its side wall opening into the vertical passage and of a less length than the passage, a slide for each post, each slide rectangular in cross-section and entered into the vertical passage and having a lateral neck or web passing through the lateral slot of the post on the side adjacent to the longitudinal center of the swinging bar, a screw entered into the closed bottom of each post and limiting the downward movement of the slide in the post, a saw-guide carried by the lateral neck or web of the slide with its lower end in line with the lower end of the neck or web for the guide to overhang the post, each guide having a vertical slot in line with the pivotal center of the horizontal swinging bar, and a strip extending from the pivotal point of the swinging bar forwardly to and alongside of the front vertical post and having a groove in its upper face in line with the vertical slot of the saw-guide, substantially as described.

3. In a miter-box, the combination of a bed or base frame having in its upper surface a depressed quadrant-shaped transverse center formed by cutting away the upper face of both the front and rear side rails each side of the transverse center of the box on converging lines from front to rear and diagonal cross-pieces extending from side rail to side rail and converging from front to rear parallel with the convergence of the cut-away ends of the side rail, each diagonal cross-piece having its upper face in a plane with the upper face of the cut-away sections of the rails, a forwardly-projecting rim at the front or base of the quadrant-shaped depressed center having its edge curved on the arc of a circle struck from the apex center of the quadrant and provided with a series of notches, a bar on the under side of the bed or base frame pivoted at its rear end on the center line and at the apex end of and swinging beneath the depressed center, a vertical post at each end of the bar, a slide for each post vertically movable therein, a saw-guide for each slide connected with the slide to overhang the post, each saw-guide having a vertical slot in line with the pivotal center of the horizontal swinging bar, a strip extending from the pivotal

formed by cutting away the upper face of both the front and rear side rails each side of the transverse center of the box on converging lines from front to rear and diagonal cross-pieces extending from side rail to side rail and converging from front to rear parallel with the convergence of the cut-away ends of the side rails, each diagonal cross-piece having its upper face in a plane with the upper faces of the cut-away sections of the rail, a bar on the under side of the bed or base frame pivoted at its rear end on the center line and at the apex end of and swinging beneath the depressed center, a vertical post at each end of the bar, each post having a vertical passage rectangular in cross-section open at the top and closed at the bottom and each post having a lateral slot through its side wall opening into the vertical passage and of a less length than the passage, a slide for each post, each slide rectangular in cross-section and entered into the vertical passage and having a lateral neck or web passing through the lateral slot of the post on the side adjacent to the longitudinal center of the swinging bar, a screw entered into the closed bottom of each post and limiting the downward movement of the slide in the post, a saw-guide carried by the lateral neck or web of the slide with its lower end in line with the lower end of the neck or web for the guide to overhang the post, each guide having a vertical slot in line with the pivotal center of the horizontal swinging bar, and a strip extending from the pivotal point of the swinging bar forwardly to and alongside of the front vertical post and having a groove in its upper face in line with the vertical slot of the saw-guide, substantially as described.

4. In a miter-box, the combination of a bed or base frame having in its upper surface a depressed quadrant-shaped transverse center formed by cutting away the upper face of both the front and rear side rails each side of the transverse center of the box on converging lines from front to rear and diagonal cross-pieces extending from side rail to side rail and converging from front to rear parallel with the convergence of the cut-away ends of the side rail, each diagonal cross-piece having its upper face in a plane with the upper face of the cut-away sections of the rails, a forwardly-projecting rim at the front or base of the quadrant-shaped depressed center having its edge curved on the arc of a circle struck from the apex center of the quadrant and provided with a series of notches, a bar on the under side of the bed or base frame pivoted at its rear end on the center line and at the apex end of and swinging beneath the depressed center, a vertical post at each end of the bar, a slide for each post vertically movable therein, a saw-guide for each slide connected with the slide to overhang the post, each saw-guide having a vertical slot in line with the pivotal center of the horizontal swinging bar, a strip extending from the pivotal

point of the swinging bar forwardly to and alongside of the front vertical post and having a groove in its upper face in line with the vertical slot of the saw-guide, a fixed upwardly-projecting guide-block on top of the swinging bar adjacent to the front end thereof, a sliding latch or catch mounted on the upper side of the swinging bar and having an acting end to engage with the notches of the circular rim at the front or base of the quadrant-shaped opening, a chamber or recess in the under side of the sliding latch or catch to receive the guide-block, a longitudinal slot in the top of the latch or catch, a guard-plate

above the sliding latch or catch, a screw connecting the front end of the grooved longitudinal strip and the guard-plate with the block of the swinging bar, a pull at the front end of the sliding latch or catch, and a coiled spring between the fixed block of the swinging bar and the acting end of the sliding latch or catch, operating to advance the latch or catch into engagement with a notch on the rim, substantially as described.
